United States Patent Office

Des. 223,837
Patented June 13, 1972

223,837

COMBINED BOOK SUPPORT RACK AND PLANTER

Roy C. Martin, 294 Hanover St., Boston, Mass. 02113

Filed May 27, 1970, Ser. No. 23,171

Term of patent 14 years

Int. Cl. D6—99

U.S. Cl. D33—2

FIG. 1

FIG. 2

FIG. 3

FIG. 4

FIG. 1 is a top plan view of a combined book support rack and planter showing my new design,

FIG. 2 is an end elevation thereof,

FIG. 3 is a side elevation thereof, and,

FIG. 4 is a view in perspective showing the device inverted for use as a planter.

I claim:

The ornamental design for a combined book support rack and planter, as shown.
